TUBING BLEEDER

Filed July 19, 1926

BY

R. L. Smart
ATTORNEY.

UNITED STATES PATENT OFFICE.

ERD V. CROWELL, OF LOS ANGELES, CALIFORNIA.

TUBING BLEEDER.

Application filed July 19, 1926. Serial No. 123,390.

This invention is a tubing bleeder of the general type disclosed in my co-pending application, Serial No. 31,018, filed May 18, 1925, and which is normally maintained in a closed position but is adapted to be readily opened by shifting a string of tubing in a well; and it is the object of the invention to anchor the tubing in a well, either manually at any desired elevation or automatically in the event of the tubing breaking, with the anchoring means in the present instance having a positive spring actuating means instead of being actuated simply by the fall of the string of tubing as described in my above mentioned co-pending application, and the bleeder control connected to the anchoring means so as to provide an extremely simple but practical construction.

The invention will be readily understood from the following description of the accompanying drawings, in which:

Fig. 1 is a side elevation, partly in axial section, of a tubing bleeder constructed in accordance with the invention and shown in closed position.

Fig. 2 is a similar view showing the tubing bleeder open.

Figs. 3 and 4 are transverse sections on the lines 3—3 and 4—4 of Fig. 1.

A usual string of casing 1 extends into the well bore 2, and a string of tubing 3 extends downwardly through the casing in spaced relation from the wall thereof. A tubing catcher of the conventional "spring and weight" type is adapted for limited sliding of the entire string of tubing relative thereto; and by providing a normally closed port in the string of tubing and opening said port by the limited sliding movement of the string of tubing relative to the anchored catcher, a practical and efficient tubing bleeder is formed. The normally closed port which is adapted to form the tubing bleeder is provided in a length of pipe 4 connected by upper and lower coupling collars 5—5^a to the ends of next adjacent lengths of the string of tubing 3 in order that the bleeder may be positioned in the well at any desired level.

A sleeve 7 is slidably mounted on pipe 4 and is adapted to normally close the bleeder port 6 provided in the pipe; and the sleeve is provided with a port 8 which is adapted to align with the bleeder port when pipe 4 is shifted downwardly through the sleeve,

thereby opening the bleeder port. When the construction embodies the use of the sleeve 7 as a closure means for a bleeder port, the bore of the sleeve is preferably provided with an elongated annular recess 9 communicating with port 8, so that any appreciable shifting of pipe 4 through the sleeve will permit fluid to drain from the tubing through port 6, recess 9 and port 8 without necessitating exact alinement of the ports.

An abutment is provided between the upper end of sleeve 7 and the pipe 4, and when the device is constructed for use as a tubing bleeder this abutment consists of a packing gland 10. A spring 11 is coiled on the pipe between the packing gland and the upper coupling collar 5 in order to yieldably shift the sleeve downwardly on the pipe to normally close port 6. Downward movement of the sleeve for closing the port is preferably limited by abutment of its lower end against a shoulder 12 on pipe 4.

After lowering the string of tubing with the tubing bleeder forming a length thereof, sleeve 7 is fixed against axial displacement so that further lowering of the string of tubing will shift pipe 4 downwardly through the sleeve for alining ports 6—8.

As an instance of this arrangement a slip support 13 is slidable on pipe 4 below sleeve 7, and spring arms 14 extend upwardly from the slip support with slips 16 carried by the spring arms adapted for expansion by sleeve 7 to engage the wall of casing 1 and thereby lock the sleeve against axial movement. For this purpose the lower end of sleeve 7 tapers downwardly to form a wedge 17 which slides down in back of the slips for expanding them when pipe 4 and sleeve 7 are lowered relative to the slip support.

A coil spring 18 is mounted on pipe 4 between the lower end of slip support 13 and the lower coupling collar 5^a, so that the spring is normally compressed by the weight of the slips and their support, thereby positioning the slips in inoperative position below wedge 17 as shown in Fig. 1. If the string of tubing breaks so that it drops suddenly, the spring 18 tends to retard the fall of the slips which are thereby expanded by the wedge 17 so as to engage the wall of casing 1 and automatically lock the sleeve 7 against further axial displacement. Continued dropping of the string of tubing by

the sliding of pipe 4 through the fixed sleeve will then compress spring 11 between collar 5 and packing gland 10 so as to lock the string of tubing against further dropping 5 when the spring is compressed to its limit; and the compression of the spring will cause the fall of the string of tubing to be gradually stopped and will thus form a cushioning means for preventing injury to the tubing.

10 The means for manually locking sleeve 7 against axial displacement so that the tubing bleeder may be operated irrespective of the functioning of the automatic catcher, comprises a sleeve 20 slidable relative to the

15 string of tubing below the slip support 13. A vertical slot 21 opens through the lower end of sleeve 20 and has a transverse slot 22 at its upper end terminating in a relatively short depending slot 23. Lug 24 which may

20 be on the coupling collar 5 is slidable in the slots, and when seated in the slot 23 limits sliding of pipe 4 relative to sleeve 20 so as to space the sleeve from slip support 13.

Bowed springs 25 depend from sleeve 20 25 and are connected at their lower ends by a collar 26 which is slidable on the string of tubing; and these springs frictionally engage the wall of the well casing to hold the sleeve 20 against turning. As a consequence

30 the string of tubing may be turned relative to sleeve 20 so as to move lug 24 along transverse slot 22 and into alignment with slot 21; and with the parts in this position, lowering the string of tubing will move the

35 lug 24 downwardly in slot 21 and thus shift the wedge 17 into position for engagement by the slips 16, which are retained in elevated position by the spring 18 and the abutment of slip support 13 against the sleeve

40 40 held against axial displacement by its springs 25.

Sleeve 7 is thus held against axial displacement by the locking engagement of the slips, and the bleeder is then readily opened

45 by further lowering the string of tubing so as to slide pipe 4 through the fixed sleeve against the tension of spring 11 until ports 6-8 are in alignment.

When the string of tubing has been 50 drained and it is desired to withdraw the same from the well, bleeder port 6 is first closed by pipe 4 sliding upwardly through the fixed sleeve 7, and continued elevation of the tubing then lifts sleeve 7 by the abutment of shoulder 12 so that the wedging engagement of slips 16 is released. The string of tubing may then be readily withdrawn with the anchoring means carried upwardly with the tubing by the abutment of lug 24 55 against the upper end of slot 21.

Preparatory to running the tubing into the casing bore, the tubing is turned so that lug 24 seats in slot 23, thereby rendering the manually controlled anchoring means inoperative; and when the tubing is at the de-

sired level it is first elevated slightly relative to sleeve 20 which is held by its springs 25, thereby alining the lug 24 with transverse slot 22 so that the tubing may be turned and then lowered for anchoring the 70 same as previously described.

When pulling the string of tubing from the well it is preferably retained in position with lug 24 in alinement with slot 21, so that the manually controlled means is automatically operative for catching the tubing in the event of breakage, irrespective of the functioning of spring 18 of the automatic catcher. The safety factor of the automatic anchor is thus increased when pulling tubing. 80

I claim:

1. A tubing bleeder for a string of tubing comprising a ported conduit forming a fixed section of the entire string of tubing, means for normally closing the conduit port adapted for axial movement of the entire string of tubing relative to the closure means for opening the port, cushioning means adapted to limit said axial movement of the entire string of tubing relative to the closure means, 90 expanding means forming a part of the closure means, a slip support, slips on said support, a spring having the slip support mounted thereon and normally compressed by the weight of the slip support to space the slips from the expanding means but adapted for expansion to engage the slips by the expanding means in the event of sudden dropping of the string of tubing, a sleeve frictionally held to permit movement 95 of the tubing relative thereto, and means for releasably locking said sleeve and tubing against relative movement, said relative movement between the tubing and sleeve causing the sleeve to engage the slip support 100 for expanding the slips by the expanding means.

2. A tubing bleeder for a string of tubing comprising a ported conduit forming a fixed section of the entire string of tubing, means for normally closing the conduit port adapted for axial movement of the entire string of tubing relative to the closure means for opening the port, means for limiting said axial movement of the entire string of 110 tubing relative to the closure means, means for anchoring the closure means against axial movement, automatic means including a spring normally compressed but adapted for expansion to positively actuate the 115 anchoring means in the event of sudden dropping of the tubing, and means for manually actuating the anchoring means at any desired level in a well.

3. A tubing bleeder for a string of tubing comprising a ported conduit forming a fixed section of the entire string of tubing, means for normally closing the conduit port, adapted for axial movement of the entire string of tubing relative to the closure means for open- 120

- ing the port, means for limiting said axial movement of the entire string of tubing relative to the closure means, means for anchoring the closure means against axial movement, and automatic means including a spring normally compressed but adapted for expansion to positively actuate the anchoring means in the event of sudden dropping of the tubing.
- 5 4. A tubing bleeder for a string of tubing comprising a ported conduit forming a fixed section of the entire string of tubing, means for normally closing the conduit port adapted for axial movement of the entire string of tubing relative to the closure means, for opening the port, means for limiting said axial movement of the entire string of tubing relative to the closure means, means for anchoring the closure means against axial movement, automatic means including a spring normally compressed but adapted for expansion to positively actuate the anchoring means in the event of sudden dropping of the tubing, and means for manually actuating the anchoring means at any desired level in a well, said manual actuation being adapted to be shifted to a position where it will become automatically operative in the event of dropping of the tubing to augment the safety factor of the automatic actuation.
- 10 5. A tubing bleeder for a string of tubing comprising a ported conduit forming a fixed section of the entire string of tubing, means for normally closing the conduit port adapted for axial movement of the entire string of tubing relative to the closure means for opening the port, cushioning means adapted to limit said axial movement of the entire string of tubing relative to the closure means, means for anchoring the closure means against axial movement, and automatic
- means including a spring normally compressed but adapted for expansion to positively actuate the anchoring means in the event of sudden dropping of the tubing.
- 15 6. A tubing bleeder comprising a ported conduit forming a fixed section of an entire string of tubing, means for normally closing the conduit port adapted for movement of the entire string of tubing relative to said closure means for opening the port, means for limiting said movement of the entire string of tubing relative to the closure means, expanding means forming a part of the closure means, a slip support, slips on the support, and a spring having the slip support mounted thereon and normally compressed by the weight of the slip support to space the slips from the expanding means but adapted for expansion to engage the slips by the expanding means in the event of sudden dropping of the string of tubing.
- 20 7. A tubing bleeder comprising a ported conduit forming a fixed section of an entire string of tubing, means for normally closing the conduit port adapted for movement of the entire string of tubing relative to said closure means for opening the port, cushioning means for limiting axial movement of the entire string of tubing relative to the closure means, means for anchoring the closure means against axial movement, automatic means including a spring normally compressed but adapted for expansion to positively actuate the anchoring means in the event of sudden dropping of the tubing, and means for manually actuating the anchoring means at any desired level in a well.
- 25 8. In testimony whereof I have affixed my signature.
